UNITED STATES PATENT OFFICE

2,007,535

EASEL

William S. Kapnek, Philadelphia, Pa., assignor to
Modern Easel Company, a corporation of
Pennsylvania

Application August 8, 1934, Serial No. 738,916

4 Claims. (Cl. 248—37)

My invention relates to improvements in easels. The object is to provide improvement in means for locking the prop in desired position of adjustment.

5 The invention comprises the main body of the easel or frame, a prop for supporting the main body in position inclined to the vertical, a strut for adjusting the degree of said inclination and a locking device operating between the prop and strut for locking the parts in required adjustment.

10 Referring to the drawing which illustrates merely by way of example suitable means for the embodiment of my invention:—

15 Fig. 1 is a rear elevation.

Fig. 2 is a side elevation of the same in open position.

Fig. 3 is a fragmentary detail on an enlarged scale showing the parts in locking position.

20 Fig. 4 is a similar view showing the parts unlocked.

Fig. 5 is a section on line 5,5 of Fig. 3.

Fig. 6 is a section on line 6,6 of Fig. 3.

25 Fig. 7 is a view in perspective of the locking member.

Similar numerals refer to similar parts throughout the several views.

30 The frame or main body 10 of the easel is provided with plate 11 secured to the back thereof by any suitable means, as for example, by points 12, which are forced through the body 10 or a layer thereof and bent over or clinched in the usual way. This plate 11 is provided with a channel portion 13 for receiving the transverse extension 14 of the prop 15 to secure the same in pivotal relation with the frame or body 10. To the body portion 10 is also secured in any suitable way the plate 16 having the channel portion 17 for receiving the transverse extension 18 of

35 the strut 19 to secure the same in pivotal relation with the frame or body 10. The prop and strut are preferably made of wire, each having parallel portions as to their main extensions as shown. The prop is pivotally secured at its upper end to the plate 11 and has a flaring loop or foot 20 at its lower end. The strut is pivoted at its lower end to plate 16 and at its upper end to a formation or yoke 21 which in turn is secured to a slide member 22. This slide member 22 is provided on its side margins with bent portions 23 to form channels for receiving the parallel extensions of prop 15 so that said slide member will normally have free sliding engagement with said prop extensions.

50 A locking member or cam 24 is pivotally se-

cured to the inner side of slide member 22 as by pivot 25, midway between the parallel extensions of prop 15. This member 24 has an arm 26 extending below the lower margin of slide 23, and is provided at its lower end with ears 27 for manual operation. The opposite margins of member 24, and flanking the pivot 25 are beveled as at 28 to facilitate the entrance of said beveled margins between the extensions of prop 15 and the adjacent under surface of slide 22. When the locking member 24 is in the position shown in Fig. 4 the slide 22 is free to move up and down upon the parallel extensions of the prop 15, and thus secure desired relative positions of strut and prop with respect to the frame or body 10. When such desired positions are secured, the member 24 is moved to the position shown in Fig. 3, in which the beveled edges of member 24 are moved into tight wedging position between the parallel extensions of the prop and the adjacent surfaces of the slide.

55 In such position of member 24, the prop and strut are securely locked together against relative movement.

It will be noted that the prop and strut are so formed that the strut may lie between the parallel extensions of the prop, so that prop and strut may lie in the same plane against the rear face of the frame or body 10, which facilitates packing and transportation.

30 The slide 22 is also provided with an eye member or extension 29 positioned on the outer side of the prop and bent outwardly from the plane of the main body of the slide, to provide a handle for adjusting the slide and also to provide means for hanging the devices on a nail or a hook when so desired.

35 What I claim is:—

1. An easel comprising a main body, a prop comprising a wire having parallel extensions, and a strut, secured all in pivotal relationship, a slide pivotally secured to the strut and slidably on said wire extensions and a locking lever connected with the slide for clamping the slide to said wire extensions.

40 2. An easel comprising a main body, a prop and a strut, secured all in pivotal relationship, a slide pivotally secured to the strut and slidably on the prop, and a locking lever associated with the slide having beveled edges movable into wedging relationship between the prop and the slide.

45 3. An easel comprising a main body, a prop and a strut, secured all in pivotal relationship, a slide pivotally secured to the strut and slidably on the prop, and a locking lever comprising a flat

plate connected with the slide and movable in a plane parallel with the adjacent surface of the slide to clamp the slide to the prop.

4. An easel comprising a main body, a prop and a strut pivoted thereto, a slide member pivoted to the strut and slidably mounted on the prop, said slide member provided with an eye extension,

positioned on the outer side of the prop and bent outwardly from the plane of the main body of the slide, to provide a handle for adjusting the slide and also to provide a hanger for the easel.

WILLIAM S. KAPNEK.
